UNITED STATES PATENT OFFICE.

GEORGE W. J. MURPHY, OF MERRIMAC, MASSACHUSETTS, ASSIGNOR TO THE
G. W. J. MURPHY CO., A CORPORATION OF MASSACHUSETTS.

CURTAIN-FASTENER.

No. 853,206.

Specification of Letters Patent.

Patented May 7, 1907.

Application filed April 2, 1906. Serial No. 309,267.

To all whom it may concern:

Be it known that I, GEORGE W. J. MURPHY, a subject of the King of England, residing at Merrimac, in the county of Essex and State of Massachusetts, have invented new and useful Improvements in Curtain-Fasteners, of which the following is a specification.

This invention relates to a fastener for carriage curtains and the like, and the object is first, to provide a device of the character described, the two members of which may be securely locked against accidental disengagement one from the other, and second, to make it impossible to leave the rotatable stud of the male member in a partially locked position, that is, the two members of said fastener are either wholly locked or wholly unlocked one from the other. In devices of like character now in use, through carelessness or accident the rotatable stud is often left in a position between its locked and its unlocked position and pressure against the curtain is apt to cause the stud to rotate to its unlocked position, thus allowing the female member to become disengaged from the male member.

The invention further consists in the combination and arrangement of parts set forth in the accompanying specification and particularly pointed out in the claims thereof.

Referring to the drawings: Figure 1 is a front elevation of my improved curtain fastener together with a portion of a curtain, partly broken away, to which the female member is fastened. Fig. 2 is a section, partly in elevation and partly broken away, on line 2—2 of Fig. 1, showing a post partly broken away to which the base of the male member is secured. Fig. 3 is a front elevation of the male member. Fig. 4 is a sectional elevation on line 4—4 of Fig. 3. Fig. 5 is a detail side elevation of the front ring of the female member. Fig. 6 is a detail front elevation of the back ring of the female member. Fig. 7 is a detail front elevation of the base of the male member. Fig. 8 is a perspective view of the base.

Like numerals refer to like parts throughout the several views of the drawings.

In the drawings, 10 is a curtain provided with a perforation 11 substantially elliptical in outline. A front ring 12 is provided with an aperture 13 adapted to register with a

perforation 11 in the curtain 10. The exterior of the front ring 12 is convex in cross section and said ring is provided with two diametrically opposite depressions 14. The front ring 12 is also provided with four prongs 15 which extend through the curtain 10 and are clenched over the back face of the back ring 16. The front ring 12 and the back ring 16 together with the curtain 10 constitute a female member 17. A male member 18 consists of a base 19 adapted to be secured to a post 20, said post being one of the supports for the top of a carriage. The base 19 is provided with two intersecting grooves 21 and 22, preferably semi-circular in cross section. The base 19 is provided with a recess 23 and an aperture 24 leading from said recess to the front of said base. The diameter of the aperture 24 is less than the width of the grooves 21 and 22. A rotatable stud 25 is provided with a convex portion 26 adapted to engage either of the grooves 21 or 22. A compression spring 27 located in the recess 23 surrounds a pivotal screw 28, said screw having screw-threaded engagement with the rotatable stud 25, whereby said screw and said stud move as one piece. The spring 27 acts to hold the convex portion 26 of the rotatable stud 25 in engagement with one of the slots 21 and 22. Sharp ridges 29 are formed by the intersection of the grooves 21 and 22.

The operation of my improved curtain fastener is as follows: When it is desired to lock the two members 17 and 18 of said fastener together, the stud 25 is rotated by the thumb and finger to the position shown in Figs. 3 and 4. The female member 17 is then placed on the male member 18 and the stud 25 is turned to a position shown in Figs. 1 and 2, the corners of said stud engaging the depressions 14, 14 said depressions aiding the groove 22 in locking said stud against accidental rotary movement. It will be seen that if the stud 25 should be released by the fingers before it has been turned a full ninety degrees, the convex portion 26 of said stud will engage the sloping sides of the groove 22 and by reason of the spring 27 pulling on said stud will cause said stud to move to the position shown in Figs. 1 and 2.

The ridges 29 formed by the grooves 21 and 22 are so formed and the spring 27 is of such tension that it is a practical impossibil-

ity for the stud 25 to remain in a half-locked position. Should the stud 25 fail to turn to its fully locked position, it will turn to its unlocked position and the operator will at once 5 notice this fact and will then turn it to its fully locked position. It will be seen that the stud 25 cannot by carelessness or accident be left in a position between its locked and its unlocked position.

10 Having thus described my invention what I claim and desire by Letters Patent to secure is:

1. As an article of manufacture, a curtain fastener comprising a male and a female member, said male member formed in two parts one rotatable upon the other, one of said parts provided with two grooves separated by sharp radiating ridges formed by said grooves, the other of said parts having a 15 convex portion adapted to engage and fit said grooves.

2. As an article of manufacture, a curtain fastener comprising a male and a female member, said male member formed in two parts one rotatable upon the other, one of said parts provided with two grooves separated by sharp radiating ridges formed by said grooves, the other of said parts having a 25 convex portion adapted to engage and fit 30 said grooves, and a spring adapted to hold said convex portions in one of said grooves and lock said parts against rotation relatively to each other.

3. As an article of manufacture, a curtain fastener comprising a male and a female member, said male member consisting of a base provided with two grooves separated by sharp radiating ridges formed by said grooves, a rotatable stud provided with a 35 convex portion adapted to engage one of said 40 grooves, and a spring adapted to hold said

stud against said base, said female member provided with an aperture adapted to receive said male member, said rotatable stud adapted to lock said male and female members together. 45

4. As an article of manufacture, a curtain fastener comprising a male and a female member, said male member consisting of a base provided with two grooves of substantially semicircular cross section separated by sharp radiating ridges formed by said grooves, a rotatable stud provided with a convex portion adapted to engage said grooves, and a spring adapted to hold said stud against said base, said female member provided with an aperture adapted to receive said male member, said rotatable stud adapted to lock said male and female members together. 50 55

5. As an article of manufacture, a curtain fastener comprising a male and a female member, said male member consisting of a base provided with two grooves of substantially semicircular cross section separated by sharp radiating ridges formed by said grooves, a rotatable stud provided with a convex portion adapted to engage said grooves, and a spring adapted to hold said stud against said base, said female member provided with an aperture adapted to receive said male member, and two diametrically opposite depressions adapted to receive two 65 70 corners of said stud.

In testimony whereof I have hereunto set my hand in presence of two subscribing witnesses.

GEORGE W. J. MURPHY.
